Patented Aug. 18, 1914.

UNITED STATES PATENT OFFICE.

WILLIAM G. MEYERS, OF MITCHELL, SOUTH DAKOTA.

MEASURING-TOOL.

1,107,436.

Specification of Letters Patent. Patented Aug. 18, 1914.

Application filed December 18, 1913. Serial No. 807,515.

To all whom it may concern:

Be it known that I, WILLIAM G. MEYERS, a citizen of the United States, residing at Mitchell, in the county of Davison and State 5 of South Dakota, have invented a new and useful Measuring-Tool, of which the following is a specification.

This invention relates to measuring tools and more particularly to a pocket rule 10 adapted to be folded compactly so as to be conveniently carried but which can be used as a triangle and as a bevel, the said tool being made up of members designed to nest together when the tool is folded but which 15 will shift relative to each other when the tool is opened out, thus to dispose the parts of the tool for use either as a bevel or as a triangle.

With the foregoing and other objects in 20 view which will appear as the description proceeds, the invention resides in the combination and arrangement of parts and in the details of construction hereinafter described and claimed, it being understood that 25 changes in the precise embodiment of the invention herein disclosed, can be made within the scope of what is claimed, without departing from the spirit of the invention.

In the accompanying drawings the preferred form of the invention has been shown.

In said drawings: Figure 1 is a perspective view of the device folded for use as a rule. Fig. 2 is a plan view. Fig. 3 is a section on line A—B Fig. 2. Fig. 4 is a 35 plan view showing the tool partly extended to form a bevel. Fig. 5 is a view showing the tool fully extended to form a triangle.

Referring to the figures by characters of reference 1 and 2 constitute similar oppositely disposed rule members having their ends beveled at 45°, the two members being oppositely disposed and being hingedly connected at the inner ends of the bevels formed at one end of the tool, this hinged connection being indicated at 3. Those ends of the members 1 and 2 which are hingedly connected are solid while the opposed ends of the members are hollow inasmuch as said members are channeled longitudinally from 50 said ends to points adjacent the hingedly connected ends. The channels have been indicated at 4.

Pins 5' are extended transversely through the channeled portions of the members 1 and 55 2 at points near the open ends of the chan-

nels and mounted on these pins are the outer ends of intermediate members 5 and 6. The inner ends of these members are cut off at right angles and are hingedly connected as shown at 7 while the outer ends of the inner members are cut off at 45° as shown at 8. Thus it will be seen that when the members 5 and 6 are brought into alinement with each other, their inner ends will come together while their outer or beveled ends 8 60 will abut against the inner walls of the channels in the members 1 and 2. Thus a triangle will be produced. Each of the members 5 and 6 has a rib 9 extending along both its upper and lower face at the outer edge 70 thereof, the thickness of these ribs being equal to the thickness of the walls of the channels 4 so that the upper and lower faces of the ribs will lie in the same plane with the upper and lower faces of the members 75 1 and 2. Furthermore the members 1 and 2 are cut away longitudinally, as shown at 10. Consequently, when it is desired to collapse the tool, the hingedly connected ends of the members 5 and 6 are pressed inwardly toward the hinge 3, thus causing the members 5 and 6 to swing into the channels 4, at the same time drawing the beveled ends of the members 1 and 2 toward each other. By 80 then swinging said members 1 and 2 together, the members 5 and 6 will become housed within the channels 4, ribs 9 fitting snugly within the cutaway portions 10, as shown clearly in Figs. 1 and 2. The hinges 3 and 7 as well as the connections between 85 the members 1 and 5 and 6 and 2 are such that considerable friction will be produced when the members are shifted and, consequently, the members will remain in any 90 positions relative to each other to which they may be adjusted until forcibly shifted out of such positions.

It will be obvious that by providing 95 graduations on the members 1 and 2, as shown, the tool can be used as a rule. By 100 swinging the members 5 and 6 outwardly into alinement, the members 1 and 2 will be spread apart so that all of the members will assume the relative positions shown in Fig. 5, thus producing a triangle. By 105 partly folding the members 5 and 6, as shown in Fig. 4, any desired bevel can be obtained.

Importance is attached to the fact that 110 all of the members of the tool are constantly

connected by means of their pivots, it being unnecessary at any time to detach one member from the other.

What is claimed is:—

- 5 1. A device of the class described including opposed measuring members hingedly connected at one end, and having their faces lying in the same planes, interposed members hingedly connected together at one end and 10 and hingedly connected at their other ends to the first named members, said interposed members having faces movable in the said planes being adapted to fold together and, when folded, to nest within the first named 15 members.
2. A device of the class described including opposed measuring members hingedly connected at one end, interposed members hingedly connected together at one end and 20 hingedly connected at their other ends to the first named members, said interposed members being adapted to fold together and, when folded, to nest within the first named members, portions of said interposed members 25 being disposed in the same planes with the corresponding faces of the first named

members and all of the members of the device having their faces movable in said planes to either extended or folded positions.

3. A device of the class described including opposed measuring members hingedly connected at one end, interposed members hingedly connected together at one end and hingedly connected at their other ends to 30 the first named members, said interposed members being adapted to fold together and, when folded, to nest within the first named members, there being longitudinal 35 ribs upon the interposed members and having their outer faces in the same planes with the corresponding faces of the first named members, said first named members being cut away longitudinally to receive the ribs 40 when the device is folded.

In testimony that I claim the foregoing as my own, I have hereto affixed my signature in the presence of two witnesses.

WILLIAM G. MEYERS.
